Primary Examiner — Richard E Chilcot(74) *Attorney, Agent, or Firm* — Masuvalley & Partners; Peter Martinez(57) **CLAIM**

The ornamental design for a sperm injection device, as shown and described.

DESCRIPTION

1. Sperm injection device

1.1 Front view;

1.2 Back view;

1.3 Left view;

1.4 Right view;

1.5 Top view;

1.6 Bottom view;

1.7 Perspective view;

1.8 First reference view;

1.9 Second reference view; and

1.10 Third reference view.

1 Claim, 10 Drawing Sheets(56)
